To all whom it may concern:

Be it known that I, TALMON A. Figure 1 is a side elevation of my new wheel design,

Figure 2 is a perspective view of the same, and

Figure 3 is an axial profile view of my design.

The salient feature of my design consists in the provision of annularly beaded portions of contrasting color with the main body of the disk and adapted to stand out from the face of the disk and be thrown into sharp relief by their contrasting colors.

I claim:

Signed at Detroit, county of Wayne, State of Michigan, this 12th day of June, 1931.
